UNITED STATES PATENT OFFICE.

MARTIN E. THOMAS, OF AUBREY, TEXAS, ASSIGNOR OF ONE-TENTH TO E. C. COFFEY, ONE-FIFTH TO IDA C. HOLMAN, ONE-FIFTH TO J. M. JONES, ONE-FIFTH TO J. B. KINHEAD, AND ONE-FIFTH TO SALLIE ZOLLARS, ALL OF AUBREY, TEXAS.

OIL-WELL DRILL BIT.

Application filed September 30, 1919. Serial No. 227,882.

To all whom it may concern:

Be it known that I, MARTIN E. THOMAS, a citizen of the United States, residing at Aubrey, in the county of Denton and State 5 of Texas, have invented certain new and useful Improvements in Oil-Well Drill Bits, of which the following is a specification.

This invention relates to drill bit devices, more particularly to devices of this character 10 employed in drilling oil wells and the like, and has for one of its objects to improve the construction and increase the efficiency and utility of devices of this character.

Another object of the invention is to provide a device of this character in which the force of a stream of water under pressure is utilized to clear the cutting members from the drill chips and thus prevent clogging.

With these and other objects in view, the invention consists in certain novel features of construction, as hereafter shown and described and then specifically pointed out in 20 the claim, and in the drawings illustrative 25 of the preferred embodiment of the invention.

Figure 1 is a front elevation.

Figure 2 is a side elevation.

Figure 3 is a bottom plan view.

Figure 4 is a longitudinal section of the stock portion of the improved device with the cutting members removed.

The improved device includes a stock or body represented as a whole at 10 and provided with means, such as a tapered thread 35 11, at one end, for the attachment of a turning rod of the usual construction, not shown.

At the end opposite to the threads 11 the stock is formed with lateral offsets 13-14, 40 the lower faces of the offsets being reversely oblique or at reverse angles to the longitudinal axis of the stock.

The stock 10 is longitudinally bored as shown at 15 in figure 4, the bore terminating 45 between the oblique faces of the offsets. The

bore 15 is designed to provide a conduit for the passage of water under pressure to remove the chips resulting from the drilling operations.

Mounted for rotation upon the oblique 50 faces of the offsets are cutting disks 16-17, each formed of circular plates having reduced cutting edges and secured by bolts or other suitable devices 18-19 to the offsets. The cutting members are disposed with their 55 confronting edges relatively close and large enough to project beyond the offsets. The cutting members extend into the path of the water flowing through the bore 15 of the stock so that the revolving cutters are constantly subjected to the force of the water.

The contiguous edges of the members 16-17 thus constantly "cut into" the flowing stream of water and deflect a portion over the faces of the cutting members outwardly 65 thus carrying the "chips" outwardly and upwardly and effectually preventing the lodgment of the chips around or upon the cutters and clogging and fouling the same.

Having thus fully described the invention, 70 what is claimed as new is:

A drill bit adapted to be coupled to a tubular rod and comprising a stock having a central continuous longitudinal bore for the uninterrupted passage of water to the tubular 75 rod and having oppositely extending lateral offsets, the lower faces of the offsets being reversely oblique, and members having continuous cutting edges and revolvably mounted on the oblique faces with their cutting edges extending into the path of the water from opposite sides as it passes through the bore of the stock, and substantially at right angles to the flow thereof, whereby particles of drilled material are 80 85 prevented from adhering to the cutting members.

In testimony whereof, I affix my signature hereto.

MARTIN E. THOMAS.
